To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my invention is fully represented in the accompanying photographic illustration, to which reference is made.

This invention relates to a new design for carpets and other fabrics in which there are two main figures of different kinds; one of these figures, containing a rose-branch, is octagonal, with alternate straight and double curved sides, and has small squares in the middles of its straight sides. The other figure is similar in outline, but without the squares, and has a geometrical figure in its center.

I claim as my invention—

The design for carpets, as shown.
